METHOD OF PREPARING DITHIOL MONOCARBOXYLIC ACIDS AND ESTERS

Milon W. Bullock, Pearl River, N. Y., and John J. Hand, New Milford, N. J., assignors to American Cyanamid Company, New York, N. Y., a corporation of Maine

No Drawing. Application December 8, 1954,
Serial No. 474,022

5 Claims. (Cl. 260—399)

This invention relates to a process of preparing organic compounds. More particularly, it relates to a process of preparing dithiol aliphatic acids and esters from benzylthio substituted keto aliphatic acids and esters.

In the copending application of one of us, Serial Number 284,205, filed April 24, 1952, was described the preparation of omega[3-(1,2-dithiolanyl)aliphatic acids, salts and esters thereof. These compounds are described as oxidation inhibitors and growth supporting factors for certain microorganisms including *S. fecalis*, *Tetrahymena geleit* and some *corynebacterium* species. The compound 6,8-dithiooctanoic acid (thioctic acid) described in the above application has been found by F. Rausch (60th Session of the German Association of Internal Medicine, April 1954) to be useful in the unconscious condition described as hepatic coma which can be completely suspended by the use of thioctic acid. The report further states that alpha keto acids are oxidized by thioctic acid and it is therefore possible to reduce the increased pyruramic acid level in the blood of man by the use of thioctic acid. Thioctic acid therefore exerts a catalytic effect on metabolism. Thioctic acid and related compounds described in the application hereinbefore referred to is prepared from a dithiol aliphatic acid such as 6,8-dithiooctanoic acid. A commercial method for the preparation of 6,8-dithiooctanoic acid is therefore highly desirable.

We have now found that dithiol aliphatic acid esters can be prepared in good yields of pure product from benzylthio substituted keto aliphatic acid esters without isolation of intermediates in a single step process. Hydrolysis of these esters yield the desired acids. The new process of preparing the dithiol aliphatic acids, we believe, can be illustrated by the following equations:

2

in which R and R' are hydrogen or a lower alkyl radical and n is a whole integer from 2 to 6. As can be seen from the equations above, it is possible to prepare Compound V by starting with Compound I or Compound III and examples hereinafter illustrate both of these possibilities. The intermediates which need not be isolated are represented by Formulas II and IV. However, it is believed that Compound III is prepared through Compound II and therefore Compound I plus alpha-toluene thiol in the reaction is equivalent to Compound III in the general process.

The preparation of the benzylthio ketoaliphatic acid esters used as starting material in the process of the present invention is described and claimed in the copending application of one of us, Serial Number 387,025, filed October 19, 1953. These intermediates can be compounds such as methyl 5-benzylthio-3-ketopentanoate, methyl 6-benzylthio-4-ketohexanoate, methyl 7-benzylthio-5-ketoheptanoate, methyl 8-benzylthio-6-ketoctanoate, methyl 8-benzylthio-6-ketononanoate, etc. In a similar manner other esters such as ethyl, propyl, butyl, amyl, etc. of these compounds can also be used in the process of the present invention.

In accordance with the equations above, the present compounds are prepared by placing the benzylthio ketoaliphatic acid ester in a hydrogenation bomb along with alpha-toluene thiol and hydrogen in the presence of a sulfactive catalyst. The sulfactive catalyst can be those described by Cope et al, Journal of Organic Chemistry 19, 385 (1953). The reaction is generally carried out at a temperature within the range of 100° C. to 250° C. at a pressure of 500 to 2500 p. s. i. for a period of from thirty minutes to ten hours. The product obtained at the first stage of the reaction is the tris-benzylthioaliphatic acid illustrated by (III) in the above equation. When this product is treated with cobalt polysulfide-acetic acid paste and hydrogen one benzylthiol group along with two benzyl groups are removed. When the reaction is substantially complete the hydrogen uptake ceases. The hydrogen bomb is allowed to cool, the catalyst filtered off and the excess acetic acid distilled off. The residue containing the desired product as a mixture of acid and ester can then be dissolved in an alcohol such as, for example, methanol and a small amount of mineral acid added and the mixture heated. The alcohol can then be distilled off

3

and the residue mixed with a further solvent such as ethyl acetate, and then mixed with an alkali methyl carbonate or hydroxide solution. The desired product which is in the organic solvent layer is separated from the aqueous layer. After removal of the solvent the product can be purified by distillation under reduced pressure. Upon saponification of the esters, the acids can be obtained and on oxidation to the cyclic disulfide, they are usually solids which can be further purified by recrystallization from a suitable solvent such as n-butyl ether, cyclohexane, nitromethane, etc.

The following examples illustrate in greater particularity the preparation of the dithiol aliphatic acids and esters of the present invention.

EXAMPLE 1

Methyl 6,8-dithioloctanoate

A 1410 ml. stainless steel hydrogenation bomb was charged with 294.4 g. (1.0 mole) of methyl 8-benzylthio-6-ketoctanoate, 186.3 g. (1.5 moles) alpha-toluene thiol, 0.125 mole of cobalt polysulfide acetic paste, and a small amount of acetic acid. The bomb was filled to 1600 lbs. with hydrogen and heated with shaking to 175° C. After about three hours the pressure had dropped to 800 lbs. The bomb was again filled with hydrogen and the temperature increased to 200° C. Hydrogen was added occasionally to keep the pressure between 1200 and 1600 lbs. After six hours total reaction time the hydrogen uptake was calculated to be 3.24 moles (theory 3 moles) and the reaction was stopped. The bomb was cooled overnight and the contents emptied out. The catalyst was filtered off and washed with methanol. The solvents were distilled off and the residue taken up in 300 ml. of methanol containing 5 ml. of sulfuric acid. The resulting solution was refluxed 90 minutes and the excess methanol distilled off. The residue was taken up in ethyl acetate and washed with water and sodium bicarbonate solution. The solvent was distilled off and the residue distilled under reduced pressure. The fractions were collected as follows:

No.	B. P. (° C.)	Press. (mm.)	Wt. g.	N _b ²⁰
1.	68-102	0.2	6.3	1.4810
2.	102-125	0.2	28.8	1.4852
3.	125-130	0.2	19.2	1.4930
4.	130-130	0.2-0.14	46.3	1.5159
5.	130-134	0.14	29.4	
6.	134-188	0.14	10.0	1.5189
7.	188-190	0.14	2.0	1.5200
8.	190-230	0.14	1.5113	
9.	Distilling residue		40.0	

Fractions 2, 3, 4 and 5 represented the product methyl 6,8-dithiolactanoate.

EXAMPLE 2

Dithiooctanoic acid

The crude ester, fractions 2, 3, 4 and 5 were combined and saponified by two hours with 25 g. sodium hydroxide in 800 ml. water and left standing overnight. The aqueous solution was acidified to pH 7 and extracted with ethyl acetate to remove an insoluble oil. Now 8 ml. of 10% ferric chloride hexahydrate was added and a rapid stream of oxygen bubbled through the solution until the deep color disappears (10 minutes). Approximately 200 ml. of ethyl acetate was added and the solution acidified with hydrochloric acid. The organic phase was separated and the solvent distilled off. The yellow oil (88.6 g.) was distilled to yield 50.2 g. of product distilling 152° C. at 0.11 mm. The distillate which crystallized in the receiver was recrystallized from 150 ml. of n-butyl ether to yield 40 g. of yellow crystals of 6,8-dithiooctanoic acid, melting point 58.5°-59° C. The yield was 19.5% based on the methyl 8-benzylthio-6-ketoctanoate.

4

EXAMPLE 3

Methyl 6,8-dithioloctanoate

A 1410 ml. stainless steel hydrogenation bomb was charged with 1.61 moles of crude methyl 6,6,8-tris-benzylthiooctanoate and 0.125 mole of cobalt polysulfide acetic acid paste. The bomb was filled to 1700 lbs. with hydrogen. The shaking was started and the bomb heated 150°-160° C. for two and one-half hours. The temperature was increased to 175° C. for two and one-half hours and to 180° C. for two hours. Hydrogen was added from time to time to keep the pressure between 800 and 1700 lbs. The total hydrogen uptake was calculated as 6.3 moles (theory 5.9). The bomb was cooled overnight, the contents emptied out, the catalyst filtered off and washed with methanol. The filtrate was stripped of solvents under the reduced pressure of an aspirator. The residue was taken up in 300 ml. methanol containing 5 ml. sulfuric acid and refluxed two hours. The methanol was distilled off at the water pump. The residue was taken up in ethyl acetate and washed with water and with sodium bicarbonate solution. The residue was subjected to vacuum distillation. The fractions were collected as follows:

No.	B. P. (° C.)	Press. (mm.)	Wt. g.
1.	to 87	0.05	172
2.	87-112	0.05	37.5
3.	112-147	0.05-0.14	23.0
4.	147-155	0.14	19.5
5.	155-180	0.14-0.4	87.0
Distilling residue.			

Fraction No. 1 was largely alpha-toluene thiol which distilled 190° at 760 mm. Fractions 2-5, inclusive, were combined with the distilling residue and rehydrogenated using 0.125 mole of cobalt polysulfide acetic acid paste catalyst and 150 ml. acetic acid as solvent. The reduction was carried out for seven hours at 200° C. with hydrogen pressures of 1000-1600 lbs. A calculated 2.5 moles was taken up. The contents of the cooled bomb were washed up as above and this rehydrogenated material again distilled.

No.	B. P. (° C.)	Press. (mm.)	Wt. g.
1.	60-107	1.0	23
2.	107-120	1.0	37
3.	120-140	1.0	37
4.	140-164	1.0-0.4	50
5.	164-200	0.4-0.3	11
6.	200-240	0.3	66
Distilling residue.			

Fractions 1-5, inclusive, from the above distillation were combined and fractionated through a 12-inch Stedman column. The fraction distilling from 152 to 158 at 3.8 mm. and weighing 69.3 g. was methyl 6,8-dithiooctanoate.

EXAMPLE 4

6,8-dithiooctanoic acid

The ester of Example 3 was saponified by standing 24 hours in a solution of 75 ml. 5 N sodium hydroxide diluted to 500 ml. The aqueous suspension was extracted with ethyl acetate to remove a small amount of second phase. The aqueous solution was diluted to two liters with water and the pH adjusted to 7 with hydrochloric acid. 5 ml. of 10% ferric chloride hexahydrate was added and oxygen bubbled through the rapidly stirred solution until the color changed from purple to light yellow. 500 ml. of ethyl acetate was added and the stirring solution acidified slowly with hydrochloric acid. The organic layer was separated and the aqueous layer extracted with 200 ml. ethyl acetate. The combined ethyl acetate solutions were dried over sodium

5

sulfate and distilled leaving 32 g. of yellow oil which crystallized when allowed to cool. The product was recrystallized from 100 ml. of n-butyl ether to yield 20.0 g. (0.096 mole) of 6,8-dithiooctanoic acid, melting point 60°-61° C.

We claim:

1. The method of preparing compounds having the general formula:

in which R is a member of the group consisting of hydrogen lower alkyl radicals, R' is a lower alkyl radical and n is a whole integer from 2 to 6, which comprises heating a compound having the formula:

in which R, R' and n are as defined above with alpha-toluene thiol and hydrogen in the presence of hydrogen ions and a sulfactive catalyst.

2. In a method of preparing compounds having the general formula:

in which R is a member of the group consisting of hydrogen and lower alkyl radicals, R' is a lower alkyl

6

radical and n is a whole integer from 2 to 6, the step which comprises heating a compound having the formula:

in which R, R' and n are as defined above with hydrogen in the presence of a sulfactive catalyst.

10 3. A method of preparing a lower alkyl ester of 6,8-dithiooctanoic acid which comprises heating a lower alkyl ester of 8-benzylthio-6-ketoctanoic acid with alpha-toluene thiol and hydrogen in the presence of hydrogen ions and a sulfactive catalyst.

15 4. A method of preparing methyl 6,8-dithiooctanoate which comprises heating methyl 8-benzylthio-6-ketoctanoate with alpha-toluene thiol and hydrogen in the presence of hydrogen ions and a sulfactive catalyst.

20 5. In a method of preparing methyl 6,8-dithiooctanoate the step which comprises heating methyl 6,6,8-tris-benzylthiooctanoate with hydrogen in the presence of a sulfactive catalyst.
